S. W. Gibbs of Albany, N. Y. Assignor to
 North, Harrison & Co. of Philadelphia, Pa.
 Letters Patent No. 345 - dated Jan. 21, 1851.
 Ante-dated Dec. 31, 1850.

The Schedule referred to in these Letters Patent, and making part of the same.

To all whom it may concern:

Be it known, that I, S. W. Gibbs, of the City of Albany and State of New York have invented, or produced a new Design for Cooking Stoves, and I do hereby declare that the following is a full & exact description of the same:

The design consists in the application of certain moldings (which are represented by a, b, c, & d. in the accompanying drawings,) and certain ornaments (represented by e, f & g) to plates, which are intended for Cooking Stoves.

In the drawings which accompany this Specification, for the more perfect illustration of the design, the several parts of the stove are represented as follows, viz:

Fig. 1. A lateral elevation of the stove.

Fig. 2. A front elevation.

Fig. 3. A back elevation.

Fig. 4. A birds-eye view.

a, b, c, d. Moldings.

e. f. g. Ornaments.

What I claim as my invention, and desire to secure by Letters Patent, is, the ornamental Design for a stove, as herein described and represented in the annexed drawings.
